UNITED STATES PATENT OFFICE.

FAYETTE W. SHAW AND DICK BOTTOFF, OF CLEVELAND, OHIO.

LIFTING-JACK.

1,127,294.

Specification of Letters Patent.

Patented Feb. 2, 1915.

Application filed November 1, 1912. Serial No. 729,181.

To all whom it may concern:

Be it known that we, FAYETTE W. SHAW and DICK BOTTOFF, citizens of the United States, residing at Lakewood, Cleveland, in the county of Cuyahoga and State of Ohio, have invented certain new and useful Improvements in Lifting-Jacks, of which the following is a specification.

This invention relates to an improvement 10 in lifting jacks.

This invention has for its object to provide novel means for supporting the operating mechanism of jacks of the type embodying a lifting screw and stand, whereby 15 such lifting screw may be elevated or lowered by an intermittent action, the mountings for the operating mechanism being such as to admit of the parts being quickly assembled or taken apart, with the result 20 that replacements may be effected with the greatest facility and the parts rendered accessible for any purpose.

The invention consists of the novel features, details of construction and combinations of parts which hereinafter will be more particularly set forth, illustrated and claimed.

In the drawings: Figure 1 is a perspective view of the jack; Fig. 2 is a vertical section, the screw and its supporting sleeve being in lowered position; Fig. 3 is an elevation partly in section, the screw and its supporting sleeve being raised; Fig. 4 is a section on the line 4—4 of Fig. 3; Fig. 5 is a 35 perspective view of the sleeve and the bracket which is formed integral with the same to support the handle by means of which the jack-screw is raised; Fig. 6 a section on the line 6—6 of Fig. 2. Fig. 7 is a 40 detail view of the terminal of the tubular member 42.

In the drawings 10 designates the base which supports the hollow standard 11. This standard is cylindrical and receives the 45 sleeve 12, the standard being formed with slots 11' receiving the ribs 12' of the sleeve 12. Thus a plurality of nesting ribs are provided which prevent the sleeve from turning. The sleeve is formed with a plurality of apertures 13, being maintained in adjusted position with respect to the standard by means of dogs 14 pivotally supported between the apertured lugs 15 which are formed integral with the casing at the 50 points where it is increased in thickness. These dogs are maintained with their ex-

tensions 17 projecting within the standard by means of springs 18 which are interposed between their handle portions 19 and the standard. The sleeve 12 is provided at its upper end with a flange 21 which rests upon the upper portion of the standard, when the sleeve is in its normal position within the standard. A nut 22 is arranged on the upper end of the sleeve 12, said nut being 60 formed with a plurality of apertured lugs 23 which receive screws 24, the screws extending beneath the flange 21 of the sleeve 12, the sleeve 12 being raised as the nut is raised. The jack-screw 25 extends through 70 the nut 22, being housed by the sleeve 12. A pin 25' extends transversely through said screw adjacent its base, the terminals of said pin extending within slots 25" formed in the sleeve 12. The rotation of the nut causes 75 the jack-screw to feed vertically within said sleeve, the pin 25' maintaining the same against rotation.

A collar 26 is secured to the nut by means of screws 27, said collar being formed with 80 radially extending teeth 28 which are spaced from the flange 22' of the nut. A plate 30 is interposed between the teeth 28 and the flange of the nut, said plate being provided with an extension 31 to which is bolted the 85 bracket 32 of the handle supporting member shown in detail in Fig. 5. This handle supporting member consists of the sleeve 33 which is secured to or formed integral with the bracket 32, a handle being inserted with 90 in the sleeve to engage the terminals of a pin 34 which passes through the shaft 35 which is rotatably supported by the off-set 36 of the bracket 32. This shaft supports at its terminal remote from the pin 34 a dog 95 37. This dog is formed with the tooth engaging portions 38 and 39 which when the handle is reciprocated impart movement to the nut through the medium of the teeth 28.

In adjusting the jack the same is placed 100 beneath the vehicle and the screw and sleeve lifted as an entirety until the member 41, which is arranged on the end portion of the jack-screw, contacts with the portion of the vehicle which it is desired to lift. The dogs 105 14 are then allowed to enter the apertures in the sleeve locking the same against receding within the standard. With the jack in this position, the handle 42 is inserted within the sleeve 33, said handle being provided with 110 the tubular portion 42' which receives the end portion of the shaft 35, the tubular por-

tion being provided with slots which receive the terminals of the pin 34. The handle is then rotated until the dog contacts with the teeth, it being noted that the dog is rotated in 5 a direction to the left when it is desired to raise the screw, so that the same will contact with the teeth to feed the nut to the right. After the dog has been brought to this position, the handle is reciprocated to feed the 10 screw upward to raise the vehicle, it being noted that the nut is effectually held against vertical movement with the screw by the screws 24 which pass through the apertured lugs 23, said screws contacting with the 15 flange 21 of the sleeve.

The many advantages of a construction of this character will be clearly apparent, as it will be noted that the same may be readily brought to a position where the jack-screw 20 may engage the portion of the vehicle which it is desired to lift, it being unnecessary to feed the jack-screw the entire length of the standard in raising and lowering the same, the feeding of the jack-screw only occurring 25 during the actual lifting of the vehicle. It will also be noted that the construction is such as may be easily and economically manufactured and that the various parts may be readily assembled.

30 It will be noted that the handle member which is received by the tubular portion 42' of the bracket 32 is removable. Thus the jack may be conveniently placed within the tool box of a motor vehicle, attention being 35 called to the fact that the handle supporting sleeve may be rotated with respect to the standard in order that the jack may lie flat in the tool box. The advantages of this construction will be noted, as the jack when not 40 in use will occupy but little space, being

readily placed within a narrow tool receptacle.

Having described our invention, what is claimed is:

In a lifting jack of the character specified, 45 the combination of a hollow member having an outer flange at its upper end, an internally threaded member mounted upon the hollow member and having an outwardly extending base to extend over the hollow member 50 and formed with a depending portion embracing the sides of the flange thereof, means fitted to the depending portion of the internally threaded member and engaging over the flange of the hollow member, an 55 externally threaded member disposed within the hollow member and having screw-threaded engagement with the internally threaded member, means for preventing relative rotation of the externally screw-threaded member and hollow member, a 60 plate mounted upon the outwardly extending part of the internally threaded member and free to turn thereon, retaining means secured to the internally threaded member 65 and extending over the plate to prevent vertical displacement thereof, and actuating means mounted upon the said plate and co-operating with the retaining means by an intermittent motion to effect rotary movement 70 of the internally threaded member, and a longitudinal movement of the externally threaded member.

In testimony whereof we affix our signatures in presence of two witnesses.
